COLLAPSIBLE CARDBOARD DISPLAY DEVICE

John V. Horr, North Tarrytown, N. Y., assignor to
Einson-Freeman Co., Inc., Long Island City,
N. Y., a corporation of Delaware

Application March 31, 1943, Serial No. 481,241

18 Claims. (Cl. 40—126)

My present invention relates generally to display devices, and has particular reference to a collapsible cardboard structure primarily intended for use in store windows, on counters, and in similar places.

It is a general object of my invention to provide an improved display device composed entirely of cardboard or equivalent inexpensive sheet material, which may be adjusted at will from a collapsed substantially flat condition to an operative set-up condition.

A more particular object of my invention is to provide a device whose structural nature and surface embellishment is of such a character that when the device is set up it will simulate one or more commodities or other commercial items. The invention is primarily applicable to the depiction or representation of a commercial article such as a bottle or the like, whose simulation is capable of accomplishment by forwardly expanding or bulging a normally flat element of sheet material. Certain features of my invention are not necessarily restricted to the simulation of any particular type of commodity, but the general nature and the novel features of the present improvement are well exemplified in a device of the character herein illustrated and described, by means of which I am enabled to achieve an attractive and realistic simulation of a plurality of bottles arranged in superposed tiers.

One of the outstanding advantages of the present improved structure is its unusual simplicity. It is composed of relatively few elements of flat cardboard or its equivalent, and the component parts are of simple structural character and are capable of assembly by simple gluing or stapling operations during the course of manufacture. The finished article is of such a nature that it may be collapsed into a substantially flat condition for purposes of convenient storage and shipment. When the device is to be used, the parts swing readily into an adjusted set-up condition and the device may be locked in operative condition by an extremely simple operation requiring no particular skill on the part of the user.

The present structure is essentially of the "stepped" variety, comprising in its simplest form a flat element divided by spaced hinge lines into lower and upper steps and an intermediate riser. A characterizing feature of the structure lies in the provision of a pair of slits which extend across the lower hinge line, thus defining between them a strip which is adapted to buckle forwardly when the device is set up. Carried by the riser is a normally collapsed but expandable display piece which is positioned so as to be encountered by the buckling strip, the strip thus serving as a pusher which presses the dis-

play piece forwardly into an expanded operative condition.

In the preferred embodiment of my invention, this structural association of parts is duplicated so as to provide a series of successive tiers of display pieces arranged in staggered relationships. An easel of suitable character, preferably including a similar strip which is adapted to buckle forwardly and thereby form a brace, is associated with the device as an integral part of the structure.

I achieve these general objects and advantages and such other objects and advantages as may hereinafter be pointed out, in the manner illustratively exemplified in the accompanying drawings, in which:

Fig. 1 is a front elevational view of a device constructed in accordance with the present invention, shown in set-up condition;

Fig. 2 is a side view of Fig. 1;

Fig. 3 is a top view of Fig. 1;

Fig. 4 is a side view similar to Fig. 2 showing the device in partially collapsed condition;

Fig. 5 is a plan view of a single blank of which part of the structure of Fig. 1 may be composed;

Fig. 6 is a plan view of a blank of which the easel may be formed;

Fig. 7 is a plan view of a blank of which the lowermost tier of display pieces shown in Fig. 1 may be formed; and

Fig. 8 is a cross-sectional view taken substantially along the line 8—8 of Fig. 1.

Figures 5, 6 and 7 show certain of the basic flat blanks of cardboard or equivalent material of which the illustrated device may be formed.

Referring first to Figure 5, it will be observed that the blank is provided with a series of spaced transverse hinge lines 10, 11, 12, 13 and 14 which divide the blank into hinged panels 15, 16, 17, 18, 19 and 20. The hinge lines are so formed, by scoring or otherwise weakening the blank, that the panels are adapted to swing into alternate horizontal and vertical planes so as to define a series of steps with risers between them. Thus, the panel 15 defines the lowest step, the panel 16 a riser at the rear of this step, the panel 17 constitutes the next step, the panel 18 the riser at the rear of this step, and so on. I have chosen to show a device in which there are three steps 15, 17 and 19, and in which the steps are relatively narrow while the risers are relatively high, but it will be understood that the invention may be embodied in devices having fewer steps, or a greater number of steps, and in which the relative sizes are of different character. I have also chosen to show a device in which the risers and steps become successively narrower in an upward direction, because an attractive depiction of grouped commodities may thus be achieved, but this arrangement is merely illustrative.

In each riser I provide at least one pair of spaced longitudinal slits which extend across the hinge line at the base of the riser. Thus, in the particular device herein illustrated, I have provided three such pairs of slits in the riser 16, two pairs in the riser 18, and only one pair in the riser 20. The slits or cuts 21 form one pair in the riser 16, and it will be observed that they extend downwardly across and beyond the hinge line 10 to a point 22. I have shown these slits as being parallel and extending upwardly all the way to the hinge line 11 but it is not necessary for the purposes of the present invention that the slits be absolutely parallel or that they extend all the way to the hinge line 11. Between them they define a strip 23 which is adapted to buckle forwardly when the device is set up. To facilitate this action, there is a score line 24 at the lower end of the strip 23 and a transverse score line 25 near its upper end. Preferably, the distance between the score line 25 and the upper end of the strip 23 is equal to the distance between the score line 24 and the hinge line 10. In this way, the forward buckling of the strip 23 when the device is set up presents a pusher portion which is substantially parallel to the plane of the riser 16.

Similarly arranged in the riser 16 are the pairs of slits 26 and 27 which define between them the strips 28 and 29, respectively. Transverse hinge lines 30 and 31 facilitate the forward buckling of the strip 28, and the corresponding transverse hinge lines 32 and 33 perform the same function with respect to the strip 29.

In the riser 18 I provide two pairs of slits 34 and 35. It will be observed that each of these pairs of slits extends across and beyond the hinge line 12, and I have shown the slits extending all the way from the hinge line 13 to the hinge line 11 but it is not absolutely essential for the purposes of the invention that the slits extend upwardly as far as the hinge line 13 or downwardly as far as the hinge line 11. The strip 36 between the slits 34 is provided with a transverse score line 37, and the strip 38 between the slits 35 is provided with a similar transverse score line 39. Preferably, each of the score lines 37 and 39 is the same distance from the upper end of the strip as the lower end of the strip is from the hinge line 12.

In the upper riser 20 I provide a pair of slits 40 which extend across the hinge line 14 and which terminate, in the illustrated construction, at the hinge line 13. These slits extend upwardly to a point 41 and the upper end of the strip 42 between the slits 40 is defined by a transverse score line 43. An intermediate score line 44 is also provided so as to facilitate the forward buckling of the strip 42. The score line 44 is preferably the same distance from the line 43 as the lower end of the strip 43 (at the hinge 13) is from the hinge line 14.

It will be observed that the pairs of slits in the riser 18 are staggered or offset with respect to the pairs of slits in the riser 16, and that the same offset relationship exists with respect to the pair of slits 40 in the upper riser 20.

The blank of Figure 5 thus forms the basic stepped structure of the device. When the device is collapsed this basic structure assumes the normally flat disposition shown in Figure 5, all the panels being arranged in a single plane. When the device is set up, the blank of Figure 5 adjusts itself into the stepped relationship of panels and parts shown most clearly in Figure

2, the representation of these parts in Figure 4 serving to illustrate an intermediate stage of this adjustment. As the panels 15, 17 and 20 assume substantially horizontal positions to define the steps, the longitudinal strip portions of each riser buckle forwardly to provide pushers which act upon certain expandable display pieces which are carried by the respective risers. Several of these display pieces are illustrated in Figure 7, to which attention is now directed.

The blank of Figure 7 is composed of card-board or equivalent flexible sheet material, preferably somewhat thinner than the stock of which the blank of Figure 5 is made. By means of spaced substantially parallel fold lines 45, 46, 47 and 48, the blank is divided into sections defining a relatively wide body 49, relatively narrow side pieces 50 at each side of this body, and attachment panels 51 alongside of the side pieces 50. The body 49 is substantially wider than any of the pusher strips of the basic structure, and is shaped into conformity with the general contours of the commodity (such as a bottle) which is to be represented. In the illustrated device, the body 49 is associated with the riser 16 so that it overlies the strip 23. This assembly is accomplished by turning each of the side pieces 50 rearwardly so that it underlies the side margins of the body 49, and attaching the panels 51 to the riser 16 on the opposite sides, respectively, of the pair of slits 21. This attachment is preferably accomplished by a simple gluing operation. The display piece thus defines a normally collapsed and substantially flat structure which is nevertheless forwardly expandable (as indicated most clearly in Figure 3) when the pushing or buckling pressure of the strip 23 is exerted upon the rear surface of the body 49. When the device is completely set up, the body 49 bulges convexly forwardly, as shown in Figure 3, and the side pieces 50 converge rearwardly. By suitably embellishing the external surface of the body 49 and the side pieces 50, an effective simulation of a bottle or other commodity may be produced.

Preferably, the body 49 extends upwardly beyond the level of the step 17, thereby completely concealing the strip 23 when the device is set up.

Where more than one display piece is to be employed, as in the case of the three display pieces associated respectively with the pusher strips 23, 28 and 29, they may all be conveniently formed as integral parts of a single blank such as that shown in Figure 7. Thus, the attachment panel 51 is hinged as at 52 to one of the side pieces 53 of the adjacent display piece whose body portion is designated by the reference numeral 54. Similarly, the third display piece comprises the body portion 55 and the hinged side pieces 56, the latter being connected at their rear edges with the attachment panels 57 and 58. When the device is to be assembled, the side pieces 53 and 56 are folded rearwardly so as to underlie the side margins of the respective bodies 54 and 55, and the attachment panels 51, 57 and 58 are then glued or otherwise secured to the riser 16 in the regions between the pairs of slits 21, 26 and 27. The body 54 is thus positioned over the pusher strip 28, and the body 55 over the pusher strip 29, and the action of these strips in expanding the respective display pieces when the device is set up is the same as the action heretofore described in connection with the strip 23 and the body 49. The result is most clearly illustrated in Figure 3.

A blank of material, similar to that of Figure 7,

and constructed in like manner, is associated with the riser 18, and in the illustrated construction this blank is provided with portions which define two display pieces. A third blank is associated with the riser 20 and is constructed so as to provide a single display piece in overlying relationship to the single pusher strip 42 provided in the riser 20. The display piece blank associated with the riser 18 is designated in the present drawings by the reference numeral 59 and the display piece blank associated with the riser 20 is designated by the reference numeral 60 (see Figure 3).

Associated with these operative parts is an easel which is so constructed that it may be collapsed and adjusted into set up condition in a cooperative manner. Preferably, the easel is composed of a blank of relatively heavy cardboard stock or its equivalent, shaped substantially as shown in Figure 6. A hinge line 61 serves to connect the two sections 62 and 63 of the easel, the section 62 being arranged in a horizontal plane when the device is set up, and the section 63 being arranged in a vertical plane. Extending across the hinge line 61 are the spaced slits 64 which define a strip 65 between them. This strip is hinged as at 66 to the section 62, and at 67 to the section 63. An intermediate transverse score line 68 facilitates the forward buckling of the strip 65 when the sections 62 and 63 of the easel are adjusted into set up relationship. The strip 65 does not serve as a pusher, however, but defines a brace which helps to support the operative portions of the device. More particularly, it will be observed that the horizontal section 62 of the easel is secured to the lowest step 15 of the device, while the vertical section 63 is secured to the uppermost riser 20, the brace 65 being secured to the intermediate riser 18 (see Figures 2 and 8). The association of parts is preferably accomplished by a simple gluing procedure.

With the parts thus assembled, the device adjusts itself readily into the set-up condition of Figures 2 and 8, an intermediate relationship of parts being represented in Figure 4. To hold the device in this set-up condition, the easel is provided with at least one bracing wing hinged to the upright section 63 along a longitudinal hinge line. I have illustratively shown two bracing wings 69 and 70 hinged to the section 63 along the longitudinal lines 71 and 72 respectively. When these bracing wings are brought into rearwardly-directed substantially parallel relationship, as shown in Figures 2 and 8, they may be locked together in any convenient manner as for example by means of a tab 73 hinged to the wing 70 at 74, this tab being swung downwardly into a horizontal position and having its notched end 75 brought into engagement with a suitable slot or recess 76 formed in the corresponding portion of the bracing wing 69.

Preferably, the upright section 63 of the easel is provided with cuts 77 extending inwardly from the hinge lines 71 and 72 and defining props 78. These props form parts of the present wings and are thus hinged to the easel section 63, and they are so positioned with respect to this section of the easel that when the device is set up they dispose themselves beneath the step 19 (see Figures 2 and 8) so as to lend added support to the structure at this region.

From the description given, it will be obvious that the device is one which may be conveniently collapsed into a substantially flat condition by

merely disconnecting the tab 73 from the recess 76 and adjusting the bracing wings 69 and 70 into the position shown in Figure 6, whereupon the entire device collapses readily as indicated in Figure 4. At the same time, whenever the device is to be set up, the parts adjust themselves almost automatically into their operative relationships; and with very simple manipulation by the user, who need not be specially skilled, the device may be set up into operative condition by merely swinging the bracing wings 69 and 70 rearwardly and adjusting the tab 73 into engagement with the recess 76. During the process of setting up the device, the display pieces are automatically expanded forwardly as hereinbefore described.

While I have shown a device in which bottles are depicted, arranged in three tiers and in staggered relationships, it will be understood that any other commodity or thing may be similarly represented by suitably designing the shapes of the operative portions of the device and by providing suitable ornamentation or embellishment on the outer surfaces. It will also be understood that the display pieces need not necessarily be arranged in three tiers, or even in two tiers, since certain features of the invention are applicable to relatively simple structures in which perhaps one or possibly two or three commodities or things are the only ones depicted.

Having thus described my invention and illustrated its use, what I claim as new and desire to secure by Letters Patent is:

1. In a collapsible cardboard display device, a flat element divided by spaced hinge lines into three panels adapted to define lower and upper steps and an intermediate riser when the device is set up, said element having spaced slits extending across the lower hinge line to define a strip between the slits which buckles forwardly when the device is set up, and a normally collapsed but expandable display piece secured to the riser over said strip so as to be pressed forwardly thereby into expanded condition.

2. In a collapsible display device, the combination set forth in claim 1, said slits extending the full height of the riser, said display piece extending upwardly beyond the upper step so as to conceal said strip completely when the device is set up.

3. In a collapsible display device, the combination set forth in claim 1, said strip having a transverse score which is the same distance from its upper end as the distance from its lower end to the lower hinge line, whereby said strip when it buckles presents to the display piece a pusher portion substantially parallel to said riser.

4. In a collapsible display device, the combination set forth in claim 1, said display piece comprising a flexible body substantially wider than said strip, and side pieces extending from said body to said riser.

5. In a collapsible display device, the combination set forth in claim 1, said display piece comprising a flexible body substantially wider than said strip, and side pieces extending from said body to said riser, said side pieces being hinged to said body so as to lie flat behind the side margins of the body when the display piece is collapsed and to converge rearwardly when the display piece is expanded forwardly.

6. In a collapsible display device, the combination set forth in claim 1, said display piece comprising a flexible body substantially wider than said strip, side pieces hinged to said body

and extending from said body to said riser, and laterally-extending attachment panels hinged to the rear edges of said side pieces.

7. In a collapsible cardboard display device, a flat element divided by spaced hinge lines into three panels adapted to define lower and upper steps and an intermediate riser when the device is set up, said element having pairs of spaced slits extending across the lower hinge line to define a strip between each pair of slits which buckles forwardly when the device is set up, and a normally collapsed but expandable display piece secured to the riser over each strip so as to be pressed forwardly thereby into expanded condition, said display pieces comprising portions of a single element of flat stock secured to the riser in the regions between said pairs of slits.

8. In a collapsible cardboard display device, a flat element divided by spaced hinge lines into three panels adapted to define lower and upper steps and an intermediate riser when the device is set up, said element having pairs of spaced slits extending across the lower hinge line to define a strip between each pair of slits which buckles forwardly when the device is set up, and a normally collapsed but expandable display piece secured to the riser over each strip so as to be pressed forwardly thereby into expanded condition, each display piece comprising a flexible body substantially wider than the strip it overlies, side pieces hinged to said body at the sides thereof, and laterally extending attachment panels hinged to the rear edges of said side pieces.

9. In a collapsible cardboard display device, a flat element divided by spaced hinge lines into three panels adapted to define lower and upper steps and an intermediate riser when the device is set up, said element having pairs of spaced slits extending across the lower hinge line to define a strip between each pair of slits which buckles forwardly when the device is set up, and a normally collapsed but expandable display piece secured to the riser over each strip so as to be pressed forwardly thereby into expanded condition, each display piece comprising a flexible body substantially wider than the strip it overlies, side pieces hinged to said body at the sides thereof, and laterally extending attachment panels hinged to the rear edges of said side pieces, said display piece bodies, side pieces, and attachment panels comprising portions of a single element of flat stock.

10. In a collapsible cardboard display device, a flat element divided by spaced hinge lines into four panels adapted to define lower and upper steps and a riser at the rear of each step when the device is set up, said element having a pair of spaced slits extending across the hinge line at the lower end of the lower riser and another pair of spaced slits extending across the hinge line at the lower end of the upper riser, the strip between each pair of slits being adapted to buckle forwardly when the device is set up, and a normally collapsed but expandable display piece secured to each riser over the corresponding strip so as to be pressed forwardly thereby into expanded condition.

11. In a collapsible display device, the combination set forth in claim 10, the upper pair of slits being offset with respect to the lower pair and the display pieces being correspondingly offset with respect to each other.

12. In a collapsible cardboard display device,

a flat element divided by spaced hinge lines into four panels adapted to define lower and upper steps and a riser at the rear of each step when the device is set up, said element having a pair of spaced slits extending across the hinge line at the lower end of the lower riser and another pair of spaced slits extending across the hinge line at the lower end of the upper riser, the strip between each pair of slits being adapted to buckle forwardly when the device is set up, a normally collapsed but expandable display piece secured to each riser over the corresponding strip so as to be pressed forwardly thereby into expanded condition, and an easel adapted to retain the parts in display relationships when the device is set up.

13. In a collapsible display device, the combination set forth in claim 12, said easel comprising hingedly connected portions one of which is secured to the lower step and the other to the upper riser.

14. In a collapsible cardboard display device, a flat element divided by spaced hinge lines into four panels adapted to define lower and upper steps and a riser at the rear of each step when the device is set up, said element having spaced pairs of spaced slits extending across the hinge line at the lower end of the lower riser and spaced pairs of spaced slits extending across the hinge line at the lower end of the upper riser, the strip between each pair of slits being adapted to buckle forwardly when the device is set up, and a normally collapsed but expandable display piece secured to each riser over each corresponding strip so as to be pressed forwardly thereby into expanded condition, the upper pairs of slits being staggered with respect to the lower pairs and the display pieces in the upper tier being correspondingly offset with respect to those in the lower tier.

15. In a collapsible cardboard display device, a flat element divided by spaced transverse hinge lines into panels adapted to swing into alternate horizontal and vertical planes when the device is set up, thereby defining a series of steps with risers between them, and an easel comprising hinged horizontal and upright sections, said easel being provided with a pair of slits extending across the hinge line, the strip between said slits being adapted to buckle forwardly to define a brace, the horizontal section of the easel being secured to the lowest step, the upright section to one of the upper risers, and the brace to one of the intermediate risers.

16. In a collapsible device, the combination set forth in claim 15, said easel being also provided with at least one bracing wing hinged to the upright section along a longitudinal hinge line.

17. In a collapsible device, the combination set forth in claim 15, said easel being also provided with at least one hinged prop adapted to underlie one of the intermediate steps when the device is set up.

18. In a collapsible device, the combination set forth in claim 15, said flat element being provided with pairs of spaced longitudinal slits extending across certain of said hinge lines, the strip between each pair of slits being adapted to buckle forwardly to define a pusher, and a normally collapsed but expandable display piece secured over each pusher so as to be pressed forwardly thereby into expanded condition.

JOHN V. HORN.
